UNITED STATES PATENT OFFICE.

SAMUEL B. SHELDON, OF DULUTH, MINNESOTA.

GAS-PRODUCER.

1,350,475.

Specification of Letters Patent. Patented Aug. 24, 1920.

Application filed November 4, 1918. Serial No. 260,995.

To all whom it may concern:

Be it known that I, SAMUEL B. SHELDON, a citizen of the United States, residing at Duluth, in the county of St. Louis and State 5 of Minnesota, have invented certain new and useful Improvements in Gas-Producers, of which the following is a specification.

This invention relates to gas producers and more particularly to gas producers of 10 the rotary body type.

The object of this invention is to provide a simple and effective gas producer arrangement wherein the parts including the rotary body, coöperate in a novel manner to meet 15 the requirements for successful commercial operation, the poker mechanism being arranged to operate in a manner to maintain the fuel bed in a uniformly porous condition.

20 These and other objects are accomplished by means of the arrangement disclosed by the accompanying sheets of drawings, in which—

Figure 1 is a fragmentary vertical trans- 25 verse sectional view of a gas producer embodying my invention,

Fig. 2 is a plan view thereof, and

Fig. 3 is a detail view of the cable suspension means and the manner of connecting 30 the cables to the pokers.

Referring to the figures of the drawings, it will be noted that I have shown a gas producer having a body 10 which, in this particular instance is a rotary body. This 35 body 10 is provided with a stationary top 11 which is provided with a vertically extending annular flange 12 extending down into the annular channel member 13 on the top of the body 10, the channel 13 being 40 provided with a sufficient quantity of water to form a seal to prevent the escape of gas.

Mounted within the body of the producer are pokers 14, which, preferably are arranged in a manner to treat the entire fuel bed during one complete rotation of the body 10, that is to say, that one of the pokers 14 treats the fuel in the outer circular portion of the fuel bed and the other poker 14 treats the fuel in the inner circular portion 50 of the fuel bed. These pokers are provided with shanks 15 each of which extends through a ball member 16, which, with a socket 17 mounted on the top 11 forms a ball and socket joint whereby the active end 55 of the poker may lag when it is within the fuel bed and the body 10 is being rotated.

The opening 18 in the casting forming part of the socket 17 is sufficiently large especially in the lateral line of movement of the poker to permit the active end of the pokers 60 14 to lag the necessary amount. Each poker shank 15 is provided with a cross bar 19 to the ends of which cables 20 are connected which pass over the pulleys 21 and which terminate in a single cable passing around its associated pulley 23, the cables 22 in turn being connected to their corresponding sheaves 24. In this connection it will be noted that one of the cables 22 is connected on one side of its sheave 24 and the 65 other cable 22 is connected on the other side of its sheave. These sheaves are mounted upon a shaft 25 which is oscillated back and forth by any suitable mechanism, such, for instance, as the crank arrangement 26, here 70 shown. By means of the connection between the sheaves 24 and the poker shanks 15, it is apparent that as one of the pokers is positively raised, the other is permitted to lower by gravity as a result of its own weight. 75 The particular advantage in having the pokers lower by gravity instead of being positively thrust into the fuel bed is that the pokers are permitted to sink into the fuel bed in accordance with the condition there- 80 of. The pokers will sink into the fuel bed a certain predetermined amount unless otherwise stopped by the resistance of the fuel forming the fuel bed. It is clear that if the fuel bed is relatively free of chunks 85 90 of coal the pokers will sink into the fuel bed substantially the same amount throughout the entire bed. If, on the other hand, in lowering, the pokers encountered a relatively large chunk of coal the resistance to 95 the downward poker movement is increased, and in this connection it is to be noted that if the pokers were positively driven an undue packing of the fuel bed would result. However, with the arrangement herein disclosed the pokers sink into the fuel bed by 100 their own weight and in a manner to maintain the fuel bed in a uniformly porous condition. As the body rotates, it is apparent that the working ends of the pokers will 105 lag a certain amount when said ends of the pokers are sunk into the fuel bed, thereby causing the fuel bed increment by increment to be disturbed slightly in the lateral direction which is to advantage in manufac- 110 turing gas.

It is my intention to cover all modifica-

tions falling within the spirit and scope of the following claim.

I claim:

In a gas producer, the combination of a
5 rotary body, a stationary top therefor sealed with respect to the body to prevent the escape of gas, said top having a plurality of relatively large poker receiving openings therein, a plurality of vertically movable
10 pokers extending loosely through said top openings to permit the pokers, when in the fuel, to lag as the body rotates, closures for said openings including ball and socket

joints to permit the pokers to lag, the poker shanks being regularly vertically and reciprocally movable through the balls respectively of said joints, poker actuating mechanism, and a flexible member extending between each of said pokers and said actuating mechanism whereby the pokers are 15 raised positively and lowered solely by gravity at regular intervals to maintain the fuel bed in a uniformly porous condition.

Signed at Duluth, Minnesota, this 29th day of Oct., 1918.

SAMUEL B. SHELDON.
